E. J. ARMSTRONG.
STEAM ENGINE.
APPLICATION FILED JAN. 5, 1916.

Patented Oct. 18, 1921.

UNITED STATES PATENT OFFICE.

EDWIN J. ARMSTRONG, OF ERIE, PENNSYLVANIA, ASSIGNOR TO BALL ENGINE COMPANY, OF ERIE, PENNSYLVANIA, A CORPORATION OF PENNSYLVANIA.

STEAM-ENGINE.

1,393,736.

Specification of Letters Patent.

Patented Oct. 18, 1921.

Application filed January 5, 1916. Serial No. 70,416.

To all whom it may concern:

Be it known that I, EDWIN J. ARMSTRONG, a citizen of the United States, residing at Erie, in the county of Erie and State of Pennsylvania, have invented new and useful Improvements in Steam-Engines, of which the following is a specification.

This invention relates to steam engines and consists in certain improvements in the 10 construction thereof as will be hereinafter fully described and pointed out in the claims.

More particularly the invention relates to steam engine valves and the parts immediately connected therewith.

The invention is illustrated in the accompanying drawings as follows:—

Figure 1 shows a side elevation, partly in section, of an engine cylinder and steam chest.

Fig. 2 an elevation of the valve.

Fig. 3 an enlarged view, partly in section, of one of the valve heads.

Fig. 4 a fragment of one of the valve 25 rings.

Fig. 5 an end view of the valve rings.

1 marks the steam engine cylinder, 2 the piston, 4 the steam chest, 5 the ports leading from the steam chest, 6 the steam chamber 30 of the steam chest, 7 the exhaust chambers of the steam chest, 8 a valve bushing arranged in a bar 9 of the steam chest, 10 shoulders at the ends of the bushing for positioning the bushings endwise, 11 press 35 pins secured to the steam chest covers 12 and arranged against the ends of the bushings 8 for holding the bushings in place.

The bushings 8 are of such a length as to leave a slight space between their meeting 40 ends. The meeting ends are arranged within the web 13 and the space 14 is thus provided which forms a convenient receptacle for delivering oil to the valve. This is done through a passage 15 extending to the outside of the steam chest.

The valve is made up of the heads 16, and the guide 17, the guide being connected with the heads by the bars 18. The guide operating in the bushings or sleeves 8 forms 50 a perfect support for the valves and being solid assists the heads in supporting the weight of the valve and in sustaining the disturbing effect of varying pressures.

The valve head has a ring support made 55 up of the parts 19 and 20, the part 19 being

formed integrally with the bars 18 and the part 20 being secured to the part 19 by means of screws 21. A groove 22 is formed centrally of the head between the parts 19 and 20. Split rings 23 are arranged in the 60 groove thus formed, the points of separation being at 25. These rings engage the inner surfaces of the inner main split ring and assist in expanding the main split ring.

The part 20 is provided with a ring supporting surface 26 and the part 19 with a ring supporting surface 27. These surfaces have the annular grooves 28 thus forming one of these grooves at each side of the closure rings 24. An inner main split ring 29 is arranged on the surfaces 26 and 27. It is separated at 30 (see Fig. 5) and has a series of radial perforations 29^a (see dotted lines in Fig. 3) which lead through the split ring and to the grooves 28. An outer main 70 split ring 31 is arranged over the inner main split ring 29. It has a point of separation at 32 (see Fig. 5) this being out of register with the separation 31 in the ring 29. The inner ring 29 has perforations 33 and these 75 register with perforations 34 in the ring 31. Pins 35 are placed in these perforations, the pins having heads 36 which rest on the surfaces 26 and 27. The outer end of the outer ring 31 has an undercut groove 37 and the 80 flanged ring 38 has its outer periphery coincident with the periphery of the ring 31 and its inner flange extending into the groove 37. This ring has a point of separation at 39. A shoulder 40 is arranged on the 85 outer end of the part 20 and when the part 20 is secured in place on the part 19 this 90 assembles the rings, holds them against axial movement and forms an end closure over the opening 39.

The ring 31 has an inner annular groove 41 at its inner end and an end closure ring 42 is arranged within this groove, the ring 42 having a point of separation at 44. The ring 42 is arranged over a shoulder 45 at 100 the inner end of the surface 27. A slight annular space 46 is left between the inner periphery of the ring 42 and the outer surface of the shoulder 45. Thus steam penetrating between the end of the head and 105 the bushing passes through the opening 44 into the space 46, the purpose of this being to subject the rings at the inner end of the valve to a balancing steam pressure within the rings, it being understood that in ordi- 110

nary practice the steam practically at steam chest pressure extends inwardly some distance from the end of the valve and it is the purpose of this feature to balance this pressure. In order to close off this steam from further endwise movement through the head an annular shoulder 47 is arranged on the inner periphery of the ring 42 and extends into a groove 48 in the end of the 10 ring 29.

The rings 38 and 42 have the slots 43 through which the pins 35 extend. In this way the different rings are locked so that the points of separation are maintained in 15 staggered relation. This is true not only of the rings 29 and 31 but also by means of the slot 43 of the rings 38 and 42.

The rings 31 have the perforations 31^a which are maintained in register with the 20 perforations 29^a in the ring 29. Thus there is at all times a direct communication between the outer surface of the valve and the annular grooves 28. These valves are subjected to rapid variations of pressure as 25 they cover and uncover the steam ports, thus creating an unbalanced condition with relation to the rings. The result of which is to force the rings off their seats and permit excessive leakage. On the other hand, where 30 this has been overcome the outward pressure has been such as to seriously impede the free working of the valve. In the present structure numerous holes are provided so that there is a nearly instant balancing of the 35 pressures within the rings and without the rings at all times, thus resulting at all times in a free working of the valve and at the same time through the spring pressure of the rings a maintenance of a tight joint. 40 While I have shown pronounced grooves 28 for carrying the steam into a position to equalize pressures, it will be understood that the rings themselves ordinarily leave a space which will with proper openings through 45 the rings largely accomplish this purpose. It will be also understood that the point of separation of the ring may form a means of communication through the ring.

It will be noted that with the plurality of 50 openings 31^a there are always some of the openings positioned to open into the ports. For this purpose the openings 31^a are preferably made numerous enough and close 55 enough together so as to obviate any possibility of all of them being closed by the bridge walls across the ports. A less number of openings might be used, especially if care were taken to have an opening lead to a port so that the steam pressure of the 60 port would be instantly communicated to the interior of the rings so as to affect the balanced condition. It will be noted that the openings 31^a are in communication with the port during the entire period of the clo-

sure of the port by the valve and also that 65 these openings are in communication with the port during a portion of the opening of the valve especially that part of the opening where there is a violent variation of steam pressure in the port. This is accomplished 70 by a relation of the openings in the face of valve as regards the width of the port as to bring about this result.

What I claim as new is:—

1. In a valve head, the combination of a 75 ring support; a main split ring; an auxiliary split ring having an axial flange extending under the main split ring; a closure flange extending inwardly from the axial flange; and means for admitting steam under 80 the auxiliary ring from the steam end of the head.

2. In a valve head, the combination of a ring support; an inner main split ring on 85 said support having an annular groove at the steam end; an outer main split ring on the inner main split ring, said outer and inner rings having registering openings from the outer surface of the outer ring through the inner ring; an auxiliary ring 90 at the steam end of the outer main split ring having an axial flange extending within the outer main split ring and an inwardly extending flange extending into the groove in the end of the inner main split ring; and 95 means for conveying steam near the steam end of the head under the auxiliary ring.

3. In a valve head, the combination of a ring support having an annular groove 100 therein; an inner main split ring arranged on the valve support and extending at each side of the groove; inner closure rings arranged within the groove; an outer main split ring on the inner main split ring, said outer and inner main split rings having 105 registering openings leading from the outer surface of the outer split ring through the inner split ring at each side of the groove in the ring support; an auxiliary ring at the steam end of the outer main split ring 110 having an axial flange extending under the outer main split ring; means for conveying steam under said auxiliary split ring; an auxiliary closure ring at the opposite end of the outer main split ring; and closures 115 for said auxiliary rings.

4. In a steam engine, the combination of a steam chest; valve bushings in the steam chest; supports for the ends of the bushings, said bushings having a space between their adjacent ends forming an oil receptacle and said chest having a passage leading from said space; and a valve arranged in the bushing having a guide operating over said space between the ends of the bushings.

In testimony whereof I have hereunto set my hand.

EDWIN J. ARMSTRONG.
